UNITED STATES PATENT OFFICE

169,054

RADIO CABINET

Robert D. Budlong, Skokie, Ill., assignor to Zenith
Radio Corporation, a corporation of Illinois

Application February 29, 1952, Serial No. 18,733

Term of patent 7 years

(Cl. D56—4)

To all whom it may concern:

Be it known that I, Robert D. Budlong, a citizen of the United States, residing at Skokie, in the county of Cook, State of Illinois, have invented a new, original, and ornamental Design for a Radio Cabinet, of which the following is a specification, reference being had to the accompanying drawings, forming a part thereof.

Figure 1 is an end perspective view of a radio cabinet showing my new design.

Figures 2, 3 and 4 are front, top, and side views, respectively, of the radio cabinet.

The design of the side of the cabinet not shown is similar to the design of the side shown. The design of the rear portion of the cabinet is plain.

I claim:

The ornamental design for a radio cabinet, as shown and described.

ROBERT D. BUDLONG.
